UNITED STATES PATENT OFFICE.

JOHN M. BENJAMIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON BLANKS.

Application filed August 29, 1923. Serial No. 659,978.

The present invention relates to machines for operating upon blanks and is herein illustrated as embodied in a machine for skiving box toe blanks for use in the manufacture of 5 boots and shoes.

A type of skiving machine commonly employed for this class of work is provided with a rotary cylindrical skiving knife against which the work to be skived is fed. 10 Such machines usually comprise, in addition to the cylindrical knife, a driven feed roll which is located partially within the knife near the upper portion of its cutting edge, a presser member which is located outside the 15 knife and above the feed roll and which cooperates with the latter to feed the work, and a stationary edge gage against which the work is held while it is being fed. The presser member may, as in the case of the 20 present machine, take the form of a driven roll, such a construction being used principally for operating upon comparatively stiff pieces of work. In using machines of the above described character for skiving the 25 margins of box toe blanks, counters, or similar pieces having curved edges, the blank must be guided or controlled, manually or otherwise while being fed, so that it will be turned gradually in its own plane and its 30 curved edge held against the edge gage continuously throughout the skiving operation. Furthermore, after the margin at one edge of the blank has been skived, the blank must be repositioned relatively to the skiving 35 knife in order that the blank may be properly presented and fed to the knife to enable the latter to skive the margin around the other edge or edges of the blank. Heretofore, this repositioning of the blank has been 40 accomplished manually.

According to one feature of the present invention, there is provided a machine for operating upon two localities of a blank in which the blank, after one locality has been 45 operated upon, is automatically repositioned and presented a second time to the operating means to cause the second locality to be operated upon. In the illustrative machine, a box toe blank after having first been fed to 50 its skiving mechanism in position to have its breast margin skived is automatically repositioned and presented a second time to the skiving mechanism to have its toe margin skived.

In the manufacture of blanks it is often

desired that the angle of the skive or bevel along one edge of the blank be different from that of the skive along the other edge or edges. According, therefore, to another feature of the invention, the relative position 60 of the blank and the operating means is changed preparatory to the second operation so that the second operation produces a result which differs somewhat from that of the first. In the illustrative machine, this is 65 accomplished by automatically varying the angular position of the presser after the completion of the skiving of one edge of the blank so that the other edge will be skived 70 on a different angle.

These and other features of the invention, including certain details of construction and combinations of parts, will be described as embodied in an illustrative machine and 75 pointed out in the appended claims.

Referring now to the accompanying drawings:—

Fig. 1 is a top plan view of a machine in which the present invention is embodied, certain portions of the machine being broken 80 away;

Fig. 2 is a fragmentary plan view of one of the parts which is broken away in Fig. 1;

Fig. 3 is a side elevational view of the 85 machine;

Fig. 4 is a detail view, partially in side elevation and partially in section, showing a portion of the device for seizing and repositioning the blanks after their breast margins have been skived;

Fig. 5 is a perspective view showing the greater part of the machine;

Fig. 6 is a vertical sectional view taken substantially along the line 6—6 of Fig. 3; and

Fig. 7 is a detail sectional view of a portion of the work supporting table showing the edge gage in operative position and the pusher partially retracted.

In the drawings, the invention is shown as 100 embodied in a skiving machine of the general type disclosed in Patent No. 1,301,283, granted April 22, 1919, upon an application filed in the name of A. Latham. The machine of the present application, in common 105 with that of said patent, comprises a rotary cylindrical skiving knife 2 (Fig. 3), a driven feed roll 4, and a hollow base 6. A portion at the top of the base 6 constitutes a work support or table 8 across which the work is 110

fed while being skived. The knife 2 is carried by a main driving shaft 10 which is journaled in suitable bearings in the base 6 and the upper portion of the knife projects slightly above the top of the base in position to engage the work. The periphery of the feed roll 4 is curved longitudinally to correspond to the transverse curvature of the knife edge and said roll is yieldingly supported in such a manner that it may yield bodily away from the knife edge and also tilt about an axis which is at right angles to its axis of rotation. The feed roll 4 is driven from a feed roll drive shaft 12 through suitable gearing and the shaft 12 is driven from the main or knife shaft 10 by means of a belt. The mounting and driving connections of the feed roll 4 have not been shown in the drawings since they are or may be like those of the patented machine. The work is held against the feed roll 4 by means of a presser member which, in the illustrative machine, is a roll 14, whereas in the patented machine a stationary presser foot is employed. With the exception of the presser roll 14, the construction and mounting of which will be hereinafter described, the parts thus far mentioned are or may be similar to corresponding parts of the machine of the patent hereinbefore referred to and reference is made to said patent for the details of construction of said parts.

In accordance with the present invention, the box toe blanks or other pieces to be operated upon are stacked one above another in a magazine 16 with the lowermost blank resting upon a portion of the feed table 8 somewhat to the rear and at one side of the co-operating feed and presser rolls. The blanks are fed edgewise and one by one from the bottom of the magazine 16 by means of a reciprocating feed plate or pusher 18 by means of which they are successively positioned upon the feed table as shown by full lines at 20 in Fig. 1. While being thus transferred from the magazine, each blank rides over a yielding edge gage 22 on the feed table. As shown in Fig. 7 the edge gage 22 consists of a thin strip of spring steel having one end secured at 23 to the feed table 8 and having its opposite end bent downwardly to form a gaging shoulder 24. The edge gage strip 22 is arranged so that normally it is inclined upwardly in the direction of feed of the blanks and the shoulder 24 operatively positioned in the path of the blanks. As a blank is fed over the pusher, the strip 22 is forced downward by the blank, the shoulder portion 24 being depressed into an aperture 25 in the table 8, to permit the blank to pass thereover without being lifted above the table. When the pusher 18 has reached the limit of its feeding movement the blank is positioned as shown at 20 in Fig. 1, the curved breast edge

of the blank being in contact with the forward and correspondingly curved face of the pusher, and one corner of the blank is located between the feed and presser rolls, the latter being then separated by a distance somewhat greater than the thickness of the blank. The presser roll is then lowered to engage the blank yieldingly and the presser and feed rolls, both of which are continuously driven, co-operate to feed the blank past the rotating skiving knife. As the presser roll is lowered, a presser foot 26 is depressed against the upper face of the blank and presses the blank against the feed table while the blank is being fed. The presser foot 26 acts as a drag to oppose frictionally the feed of the blank and the presser foot is so located relatively to the bite of the feed and presser rolls that the drag exerted thereby causes the curved breast edge of the blank to hug the forward edge of the pusher 18 as the blank is being fed. Thus the blank is guided or controlled in such a way as to insure that a scarf or bevel of uniform width will be made along and throughout the length of the breast margin of the blank. After the breast margin of the blank has been skived, the blank occupies the position indicated by dotted lines at 28 in Fig. 1. The presser roll 14, together with the presser foot 26, is then lifted from the blank and the latter is seized by an oscillating gripper device 30 and thereby swung in its own plane sharply about the corner last presented to the skiving knife, this movement continuing until the blank is repositioned as shown by dotted lines at 32 in Fig. 1, the blank then being presented to the grip of the feed and presser rolls in proper position for the skiving of the margin around the toe. During this repositioning of the blank, the pusher 18 is being retracted into position to remove another blank from the magazine. As soon as the pusher has been withdrawn from above the edge gage strip 22, the latter rises by reason of its spring tension and the shoulder 24 is thus lifted into position to engage the curved edge around the toe of the blank so as to guide the blank while its toe margin is being skived, the gage shoulder 24 at this time performing a function similar to that of the curved forward edge of the pusher when the pusher is in its forward position and the blank is being fed for the skiving of its breast margin. The presser roll 14 and the presser foot 26 are then lowered and the blank is again fed past the skiving knife, the presser foot serving to control the feed of the blank by causing the curved edge of its toe portion to hug the shoulder 24 of the edge gage so as to insure the cutting of a bevel of uniform width around the toe margin of the blank. While the presser roll and the presser foot are lifted from engagement with the blank to enable the latter to be re-

positioned by the swinging of the gripper device 30, the presser roll may be tilted to vary the angle of its axis relatively to the knife edge and thus to cause the toe margin 5 of the blank to be beveled at a different angle from that of the breast margin of the blank. After the margin around the toe of the blank has been skived, the presser roll and the presser foot are again lifted to 10 free the blank and the presser roll is tilted back to its original angular axial relation to the knife edge preparatory to operating upon the breast margin of the succeeding blank. By this time the feed plate 18 15 and the gripper device 30 have also been restored to their initial positions, and the machine is ready to start another cycle of operations.

The magazine 16 for holding the blanks 20 to be operated upon comprises a rear wall 34 having a horizontal curvature corresponding to that of the breast edges of the blanks, and side walls 36 which are disposed at an angle to the rear wall corresponding to the angles 25 defined by the corners of the blanks. One of the side walls 36 may be formed integrally with the rear wall as shown while the other side wall may be releasably secured to the rear wall with provision for adjustment toward and from its companion side wall, as indicated at 38, thereby adapting the magazine to hold blanks of different sizes. The magazine is supported by a post 40 which rises from the base 6 and extends 30 through a bracket 42 carried by the magazine. The bracket 42 is secured to the post 40 at such an elevation that the lower edges of the magazine walls will be spaced above the feed table 8 sufficiently to permit the 35 feed plate 18 to reciprocate between the feed table and the bottom edge of the magazine walls and to permit the lowermost blank in the magazine to be removed by the forward stroke of the feed plate. The bracket 42 40 may be adjustably secured to the post 40 so that the space between the magazine walls and the feed table may be varied to accommodate different thicknesses of blanks.

The feed plate or pusher 18 is of the general triangular shape shown in Fig. 1 and its forward edge is curved as shown at 44 to conform to the curvature of the breast edges of the blanks. The thickness of the feed plate is preferably somewhat less than that 55 of the blanks to insure against the possibility of engaging two blanks at a time in the magazine. The feed plate is movable in a rectilinear path to feed the blanks into position to be engaged by the feed and presser rolls. 60 To this end the feed plate is dovetailed to slide in a guideway 45 (Fig. 5) in the feed table 8. The portion of the feed plate which slides in the guideway 45 is extended forwardly of the curved edge 44, as shown at 65 46, to provide support for the blank as it is

being fed from the magazine. The feed plate is caused to remain at rest in its forward position while the breast edge of the blank is being skived and during this time its curved forward edge functions to guide 70 the blank as it is being fed to the knife.

The feed plate 18 is reciprocated by means of a lever 50 one end of which is fulcrumed upon a fixed stud 52 (Fig. 2) rising from the base 6, while the opposite end of said lever is connected by a short link 54 with the rear of the feed plate. The lever 50 is swung to actuate the feed plate by means of a crank pin 56 which is carried by a cam disk 58 and is connected to the lever 50 at a point intermediate its ends by a connecting rod or link 60. The connections between the link 60 and the crank pin 56 and also between said link and the lever 50 are in the form of ball and socket joints which permit the link to swing slightly in a horizontal plane as said lever is swung about its fulcrum. The cam disk 58 is fixed upon a horizontal shaft 62 which is journaled in suitable bearings carried by the base 6 and which is driven through a clutch 64 whereby the cam disk is caused to make a half a revolution twice in each cycle of operations as will be hereinafter explained.

The presser roll 14 is rigidly secured upon a shaft 70 (Fig. 5) which is journaled in bearings 72 formed on a carrier 74, the inner ends of the bearings engaging opposite faces of said roll to prevent axial displacement of the roll and shaft. The presser roll 14 is shaped, as best shown in Fig. 3, so that its profile substantially corresponds to that of the feed roll 4. The angle of the bevel formed by the skiving knife is varied by tilting the axis of the presser roll to bring its longitudinally curved periphery more or less nearly parallel to the curved profile of the feed roll. In order that the presser roll 14 may be tilted axially as described, the roll carrier 74 is provided with segmental 100 ribs 76 which project outwardly from opposite sides thereof and are received in segmental guideways in the opposed sides of a bifurcated segmental carrier support 78. The center of curvature of the ribs 76 and 105 associated guideways is so located that whatever the angular adjustment of the presser roll may be the thickness of the skived edge and the shape or size of the blank will not be altered. To enable the presser roll to be 110 raised and lowered to release or engage the work, the carrier support 78 is secured to the lower end of a spindle 80 which is mounted for vertical sliding movement 115 within suitable bearings 82 and 84 supported 120 by a standard 86 rising from the base 6.

The presser roll 14 is driven continuously 125 from the feed roll drive shaft 12 throughout the operation of the machine. The connections between the presser roll 14 and the 130

shaft 12 comprise two horizontal shafts 90 and 92 and an extensible link 94. The shafts 90 and 92 are disposed at right angles to each other and are journaled in suitable bearings 6 on the base 6. The extensible link 94 comprises telescoping sections, one of which has a universal joint connection 96 with the presser roll shaft 70, while the other section of the link 94 has a universal joint connection 98 with the shaft 92. The extensible link and universal joint construction just described permits the presser roll to be raised and lowered and also to be tilted as required at different stages of the operation upon each blank. The telescoping sections of the link 94 are constrained to rotate in unison by means of a pin and slot connection 100 (Fig. 5) arranged to permit a limited amount of relative longitudinal movement of the link sections. The shaft 92 is driven from the shaft 90 through intermeshing worm gearing 102 while the shaft 90 is driven by a chain 104 which passes over a sprocket wheel 106 on said shaft and over a sprocket wheel 108 on the feed roll drive shaft 12.

The frame or support for the presser roll and the presser foot is adapted to be raised and lowered at predetermined times in each cycle of operations of the machine by means 30 of a cam-actuated lever 110, said lever being fulcrumed upon a rod 112 that is supported at its ends in suitable bearings 114. One end of the cam lever 110 is pivotally connected at 116 to an ear 117 rising from 35 the carrier support 78, while the opposite end of said lever carries a cam roll 118 which rides in a cam path 120 in the face of the cam disk 58. The cam shaft 62, to which the cam disk 58 is adapted to be connected through 40 the clutch 64, is driven from the shaft 92 through intermeshing worm gears 122 and 124, the gear 122 being fixed to the shaft 92 while the gear 124 is loosely mounted upon the cam shaft 62.

45 To secure the necessary intermittent rotation of the cam disk 58, the cam shaft 62 is adapted to be connected with the gear 124 by a clutch of the Horton type as indicated at 64. This type of clutch is so well known 50 that it need not be described in detail herein. It will be sufficient to explain that the clutch 64 has friction rollers 126 (Fig. 3) adapted rotatably to connect the two clutch elements, of which the inner or driven element is fast 55 upon the cam shaft 62 while the outer or driving element is secured to the gear 124. The friction rollers are normally held out of operation by means comprising a controller ring 128, this ring being provided, as shown 60 in Fig. 5, with a radially projecting lug 130 which co-operates with one or the other of two abutment plates 132 carried by a control lever 134. The lever 134 is mounted to rock about a fixed horizontal pivot stud 136 and 65 is actuated by a crank pin 138 projecting

into a block 140 which is slidable within the slotted rear extremity of said lever. The crank pin 138 is carried by a worm wheel 142 which is mounted upon a fixed stud 144 and is continuously driven by a worm 146 on the shaft 92. The forward end of the lever 134, which carries the clutch controlling abutments 132, is made in the form of a ring to encircle the cam shaft 62 and the abutments 132 are supported at diametrically opposite 70 points upon the inner periphery of this ring. The abutments 132 are cushioned by suitable springs 148 which absorb the shock due to the engagement of the lug 130 with the abutments. The abutments 132 are so arranged 75 at different distances from the center of the ring-shaped end of the lever 134 that when said lever is swung in one direction to throw one abutment out of the path of the lug 130 on the controller ring 128, the other abutment will be moved into the path of said lug. When the lug 130 is released the friction rollers are spring-pressed into operative positions to connect the clutch members. Thus 80 when one of the abutments 132 is disengaged from the lug 130, the clutch operates to impart a half revolution to the cam shaft 62 and is then arrested by the engagement of the lug 130 with the other abutment. 85

The cam path 120 is so designed that the 90 presser roll 14 will be raised and lowered at each half revolution of the cam disk. During the first half rotation of the cam disk the movements derived therefrom are timed to lift the presser roll from the blank after the 95 breast margin of the blank has been skived, thus permitting the gripper device 30 to reposition the blank for the skiving of the toe margin thereof. Before the movement of the cam disk is arrested the presser roll is 100 lowered into engagement again with the blank to enable the presser roll to co-operate 105 with the feed roll 4 in the further feeding of the blank. During the second half rotation of the cam disk in each cycle of operations, 110 the cam disk 58 functions to lift the presser roll from the work to free the work after its entire margin has been skived and thereafter to lower the presser roll into engagement 115 with the next blank to be operated upon. 115

In order that the presser foot 26 shall be raised and lowered simultaneously with the raising and lowering of the presser roll 14, the presser foot is carried by the frame or support 78 for the presser roll carrier. As 120 best shown in Fig. 5, the presser foot 26 is carried at the lower end of a stem 150 that is slidable in a bearing 152 formed on the carrier support 78. The presser foot is urged downwardly by a spring 154 which 125 is coiled around a reduced portion of the stem 150, the spring bearing at its lower end against a shoulder on the stem and at its upper end against a shoulder within the bearing 152, said spring being compressed 130

between said shoulders when the presser foot is in engagement with the work. The stem 150 is reduced at its upper extremity and projects above the bearing 152 and a collar 156, fixed to the projecting portion of the stem, co-operates with the upper end of the bearing 152 to limit the downward movement of the presser foot when the latter is raised above the work.

5 It is usually desirable to skive the breast margin of a box toe blank at a somewhat sharper angle than the margin around the toe thereby producing a wider scarf at the breast than at the toe. The angle of the 10 scarf is varied by tilting the presser roll axially to vary the relation of its profile to the knife edge and thus to vary the transverse angular relation to the knife edge of the marginal portion of the blank which is 15 being fed to the knife. The segmental presser roll carrier 74 is oscillated bodily with respect to the carrier support 78 for the purpose of tilting the axis of the presser roll as hereinbefore explained. This oscillatory adjustment of the presser roll carrier 20 74 is obtained by the action of a crank pin 160 (Figs. 5 and 6) which projects from one end of a horizontal stud shaft 162 that is 25 journaled in the solid upper portion of the presser roll carrier support or frame 78. The crank pin 160 works in a vertically-elongated slot 164 that is formed in an arm 166 which is rigidly secured to the presser roll carrier. As shown in Fig. 6, the arm 30 166 is secured to the carrier 74 by means of a screw 168 and is extended outwardly and upwardly from said carrier to avoid interference with the carrier support or frame 78. The stud 162 that carries the crank pin 40 160 at one end, has fixed to its opposite end a pinion 170 and intermeshing with said pinion is a driving gear 172 which is pivotally mounted upon the side of the carrier support 78 and is provided with four pins 45 174 which project from its outer face in equally spaced apart relation. Arranged to engage one of the pins upon each upward movement of the presser roll carrier support is a pawl 176 which depends from a pivot 50 stud carried by a portion of the standard 86, the pawl being provided with a laterally offset weighted portion 178 at its upper end which functions to hold the lower extremity of the pawl in cooperative relation with the 55 pins 174 on the gear 172. The arrangement is such that upon the upward movement of the presser roll carrier support 78 the pin 174 nearest the pawl 176 will engage a shoulder 180 on the pawl and the relative movement between said support and said pawl will cause the gear 172 to be turned through ninety degrees. The diameter of the gear 172 being twice that of the pinion 170, the latter will be turned through half a 60 revolution by the quarter turn of the gear 65 172 and the crank pin 160 will be actuated to oscillate the presser roll carrier and thus to tilt the presser roll to vary its axial angular relation to the knife edge. The changed relation of the presser roll to the 70 knife edge is such that when the presser roll is subsequently depressed into engagement with the margin of the blank, said margin will be presented at a somewhat greater angle to the cutting edge of the knife and thus the scarf produced by the knife will be somewhat narrower and less sharply inclined.

75 After the breast margin of the blank has been skived, the blank is swung bodily in its own plane about the corner last acted upon by the knife to reposition the blank with its curved toe edge tangent to the edge gage preparatory to the skiving of the toe margin of the blank. This repositioning of the blank is effected by means of the gripper device 30. This device comprises an arm 184 which extends radially from a sleeve 186 which surrounds the upper portion of the spindle 80 of the presser roll carrier support, said sleeve being interposed 80 between said spindle and the bearing 82 on the standard 86. The lower extremity of the sleeve 186 rests upon the bearing 84 which is also formed upon the standard 86 and in which the said spindle 80 is journaled. As 85 hereinbefore described, the radial arm 184 is formed at its outer end with a depending portion 188 carrying laterally projecting bearing lugs 190 (see Figs. 3 and 4) within which is slidably mounted a vertical spindle 90 192. At its lower end the spindle 192 is provided with a foot 194 carrying a plurality of spurs or prongs 196 which project downwardly from said foot and extend 95 through apertures in a stripper plate 198 100 carried by the depending portion of the gripper arm. Normally the foot 194 is maintained in its elevated position, with the prongs 196 retracted so that their points are shielded within the apertures of the stripper plate and are thus maintained out of the path of feed of the blank. The foot 194 is held in its elevated position by means of a shoe 200 which is located in a recess in the side of the lowermost bearing 190 and is frictionally pressed against the spindle 192 by means of a screw 202 and spring 203.

105 110 During the skiving of the breast margin of the blank the arm 184 is positioned as shown in Fig. 1, but after the breast margin has been skived the foot 194 is first depressed to project the prongs 196 into the face of the blank and then the arm 184 is oscillated to swing the blank into the dotted line position designated 32 in Fig. 1. The 115 means for depressing the foot 194 to project the prongs 196 into the blank comprises a cam lever 208 which is fulcrumed upon the pivot rod 112 beside the lever 110. One end 120 of the lever 208 carries a cam roll 210 which 125 130

rides upon the periphery of the cam disk 58 and is adapted to be engaged and lifted by a cam projection 212. The other end of the lever 208 projects into position to overlie 5 the spindle 192 when the arm 184 is at rest in the position shown in Fig. 1. Upon movement of the lever 208 by the cam projection 212, the spindle 192 is pushed downwardly in its bearings 190 and the prongs 196 are 10 caused to penetrate the material of the blank.

The rocking of the arm 184 for the purpose of repositioning the blank for the skiving of the toe margin thereof is effected by 15 means of a gear segment 216 which is affixed upon a vertical rockshaft 218 that is mounted in bearings on the standard 86. The teeth of the gear segment intermesh with segmental gear teeth 220 upon the 20 sleeve 186 of the arm 184. The rock shaft 218 is actuated by a connecting rod 222 that is pivoted at one end to an arm 224 fast on the rockshaft 218 and at the other end to the feed plate actuating lever 50 at a point 25 in line with the corresponding end of the connecting rod 60. As the arm 184 is swung about the axis of the spindle 80, the blank, which is impaled by the prongs 196, is moved 30 over the surface of the feed table, the blank turning about its corner 226 as an axis (which corner is then positioned beneath the presser roll) until the curved edge of the toe margin is brought into engagement with the yielding edge gage 22. Just prior 35 to the completion of its turning movement over the feed table a laterally projecting pin 228 on the spindle 192 is caused to ride over the inclined face of a fixed cam 230 carried by a portion of the standard 86, this 40 action raising the spindle 192 and elevating the foot 194 to retract the prongs 196 above the lower face of the stripper plate 198. The stripper plate then functions to strip the blank from the prongs leaving the blank 45 free to be acted upon by the feed roll.

After the blank has been thus positioned for the skiving of the toe margin thereof, the presser roll and presser foot are lowered by the action of the cam lever 110 during 50 the latter part of the first half rotation of the cam disk. As soon as the blank is engaged by the presser roll and pressed thereby against the feed roll, the blank is fed again past the rotating skiving knife, the 55 presser foot also engaging the blank and, by means of the frictional drag exerted thereon causes the blank to turn in its own plane as it is fed so that its curved toe margin will be held continuously against the edge gage 22. The clutch 64 is thrown out after 60 the presser roll and presser foot have been lowered and the latter are maintained in their lowered or operative positions until after the toe margin of the blank has been 65 completely skived. The lever 134 has then

been moved into such a position that the controller ring 128 is again released and the clutch thrown in to cause the presser roll and presser foot to be raised for the second time in the cycle for the purpose of releasing the completely skived work. Upon this second upward movement of the presser roll the crank pin 160 is actuated to shift the presser roll carrier back to its original angular relation to its support and thus to position the presser roll to cause the breast margin of the succeeding blank to be skived at the proper angle. Inasmuch as the crank pin is turned through 180° at each upward movement of the presser roll it will be apparent that when the presser roll is raised for the second time in each cycle of operations the crank pin will be returned to the position which it occupied at the start of the cycle and consequently the presser roll 70 will be restored to its initial axial angular relation to the knife edge. This arrangement insures that the breast margins of all blanks operated upon will have the same angle of bevel and also that the margins around the toe will all be skived at the same angle.

Although the invention has been set forth as embodied in a machine for skiving box toe and similar blanks, it should be understood that the invention is not limited in the scope of its application to the particular machine which has been shown and described nor to operation upon any particular kind of blank.

Having described my invention, what I claim as new and desire to secure by Letters Patent of the United States is:

1. In a machine for skiving blanks, the combination of a skiving knife and means initially operative to feed the blank and subsequently to act as a guide to control the direction of travel of the blank past the knife to produce a scarf of uniform width along one edge of the blank.

2. In a machine for skiving blanks, a magazine, a skiving knife, means to detach a single blank from the magazine, said means being constructed and arranged to form an edge gage, means for feeding a blank past the knife, and means independent of said feeding means for maintaining one edge of the blank in contact with the edge gage throughout the feeding movement.

3. In a machine for skiving blanks, a skiving knife, means to feed the blank past the knife, a presser roll for maintaining the edge margin of the blank in operative engagement with the knife during the feeding operation, means to vary the angular displacement of the presser roll with respect to the feeding means to permit the edge margin of the blank to be presented to the knife at various desired angles, an edge gage, and frictional means to maintain the edge of the blank in

guiding engagement with the gage during the feeding and cutting operations.

4. In a machine for bevelling the margin of a blank, a skiving knife, means for effecting relative movement between the knife and the blank and means operating after a portion of the margin of the blank has been beveled to vary the transverse angle of presentation of the blank to the knife to vary the angle of bevel produced at another portion of the margin of the blank.

5. In a machine for operating on blanks, a skiving knife, a magazine, a feed member, means for operating the feed member to feed a blank from the magazine to a position in proximity to the knife and for holding the feed member stationary to guide the blank during movement of the blank past the knife, means for feeding the blank past the knife, and means engaging the surface of the blank for frictionally opposing the feed movement of the blank past the knife to cause the blank to be held against said feed member while being cut by the knife.

6. In a machine for skiving blanks, a skiving knife, means for relatively moving the blank and knife to skive the margin of the blank progressively and entirely round the blank, and means to vary the transverse angle of presentation of the blank to the knife at a predetermined point in the relative travel of the knife and the blank to vary the angle of bevel produced by the cutting operation.

7. In a machine for skiving box toe blanks or the like, a rotary cylindrical skiving knife, feed rolls for feeding a blank to the knife, a magazine for holding a stack of blanks, and means for feeding a blank from the magazine and delivering it to the feed rolls in such a position relatively to the knife that the breast margin only of the blank will be presented to the knife, said feeding means being constructed and arranged to serve as a guide for the blank during the cutting operation thereon.

8. In a machine for operating upon blanks, an operating member, feed rolls for feeding a blank to said member, a magazine for holding a stack of blanks, a pusher for engaging one edge of the endmost blank in the stack and delivering the blank to the feed rolls in position to have the margin adjacent to said edge fed to said member, said pusher being adapted to remain stationary while the blank is being thus fed to serve as an edge gage to guide the blank.

9. In a machine for operating upon blanks, an operating member, a feed table, means for feeding a blank across the table and past said member, an edge gage on said table for guiding the blank as it is fed past said member, said gage being beveled to permit a blank to be fed transversely across the gage and substantially at right angles to the direction of feed of the blank past said member, and

means for feeding the blank transversely across said gage into position to be guided thereby.

10. In a machine for skiving blanks having two edges arranged at an angle to each other, a skiving knife, means for feeding the blank past the knife to skive one edge of the blank, and means for repositioning the blank relatively to the feeding means and knife after the blank has been skived along said edge to enable it to be skived along the other edge thereof.

11. In a machine for skiving blanks having two edges arranged at an angle to each other, a skiving knife, means for feeding the blank past the knife to skive one edge of the blank, and means for swinging the blank about the apex of the angle formed by the edges of the blank after the first edge has been skived to position the blank for the skiving of the other edge thereof.

12. In a machine for skiving blanks having oppositely and unsymmetrically disposed edges, a skiving knife and automatic means for relatively moving the knife and the blank to skive the margin of the blank progressively and entirely around the blank.

13. In a machine for skiving blanks having oppositely and unsymmetrically disposed edges, the combination with a skiving knife, of automatic means for feeding the entire margin of a blank progressively to the skiving knife to effect the skiving of the margin entirely around the blank.

14. A machine for operating upon a blank in two localities which extend at an angle to each other having, in combination, mechanism for operating upon the blank, means for feeding the blank to the operating mechanism in position to have one locality operated upon, and means for repositioning the blank relatively to the feeding means after the operation upon one locality has been completed to cause the blank to be fed a second time to the operating mechanism in position to have the other locality operated upon.

15. In a machine for skiving blanks having two edges which meet at an angle to each other, a skiving knife, means for feeding and guiding a blank relatively to said knife to cause the blank to be skived along one of said edges, and means operative after said edge has been skived for varying the transverse angular relation of the other edge and the skiving knife to cause the edges to be skived at different angles.

16. A machine for operating upon a blank in two localities thereof having, in combination, operating mechanism, means for feeding the blank to said mechanism to cause the blank to be operated upon in one locality, and means becoming operative after the operation upon one locality has been completed for repositioning the blank with respect to

the feeding means preparatory to a second presentation to the operating mechanism and for changing the relation between the feeding means and the operating mechanism.

- 5 17. A machine for operating upon a blank in two localities thereof having, in combination, operating mechanism, means for feeding the blank to the operating mechanism to cause one locality to be operated upon in a
10 given manner, a carrier for receiving the blank after it is so operated upon, automatic means operative to cause the carrier to re-position the blank relatively to the feeding means preparatory to causing the blank to
15 be fed a second time with the second locality exposed to the operating mechanism, and means for changing the relative positions of the feeding means and operating mechanism before the blank is so fed.
- 20 18. In a machine for operating upon the margins of blanks having two edges arranged at an angle to each other, an operating member, rollers for engaging opposite sides of a blank to feed it past said member,
25 means for guiding and controlling the blank while it is being fed to cause said member to operate upon the margin adjacent to one edge of the blank, means for separating said rolls to release the blank momentarily after
30 said margin has been operated upon, and means for manipulating the blank while released by the feed rolls to position it relatively to said rolls and operating member for operation upon the margin adjacent to
35 the other edge thereof.
19. In a machine for operating upon the margins of blanks having two edges arranged at an angle to each other, an operating member, rollers for engaging opposite sides of a blank to feed it past said member, means for guiding and controlling the blank while it is being fed to cause said member to operate upon the margin adjacent to one edge of the blank, means for separating said rolls to release the blank momentarily after said margin has been operated upon, and means for manipulating the blank while released by the feed rolls to position it relatively to said rolls and operating member for operation upon the margin adjacent to the other edge thereof and for again separating said rolls after both of said margins have been operated upon to enable another blank to be introduced between them.
- 55 20. In a machine for operating upon blanks having two edges arranged at an angle to each other, an operating tool, a feed table, means for feeding the blank along said table and guiding it to cause
60 said tool to operate upon one edge of the blank, means including prongs adapted to penetrate the material of the blank for shifting the blank upon the table after said edge has been operated upon and relocating
65 the blank upon the table in position to be

fed to said tool for operation upon the other edge thereof, and means for stripping the blank from the prongs after it has been thus relocated.

21. In a machine for operating upon blanks having two edges arranged at an angle to each other, an operating tool, a feed table, means for feeding the blank along said table and guiding it to cause said tool to operate upon one edge of the blank, means including an oscillatory arm for re-positioning the blank relatively to said tool for operation upon the other edge of the blank, prongs on said arm for seizing the blank, and means for moving said prongs relatively to said arm to seize the blank after one edge has been operated upon and subsequently to release the blank for operation upon the other edge thereof.

22. In a skiving machine of the type having a rotary cylindrical skiving knife, a feed roll within the knife, and a presser roll without the knife co-operating with said roll to feed the work past the knife, the combination therewith of means for automatically separating said rolls during the operation of the machine to permit the work to be repositioned between them.

23. In a skiving machine of the type having a rotary cylindrical skiving knife, a feed roll within the knife, and a presser roll without the knife co-operating with said feed roll to feed the work past the knife, the combination therewith of mechanism for adapting the machine to skive box toe blanks, comprising means for separating said rolls after the breast margin of a blank has been skived to permit the blank to be repositioned relatively to the rolls for the skiving of the margin around the toe.

24. In a machine for skiving blanks having two edges which meet in a corner, in combination, a rotary cylindrical skiving knife, a feed roll within the knife, a presser roll without the knife co-operating with said feed roll to feed a blank past the knife, and means for momentarily lifting the presser roll out of contact with the blank after one of its edges has been skived to permit the blank to be repositioned between said rolls for the skiving of the other edge of the blank.

25. In a machine for skiving blanks having two edges which meet in a corner, in combination, a rotary cylindrical skiving knife, a feed roll yieldingly mounted within the knife, a presser roll without the knife co-operating with said feed roll to feed a blank past the knife, and means for momentarily lifting the presser roll out of contact with the blank after one of its edges has been skived to permit the blank to be repositioned between said rolls for the skiving of the other edge of the blank and for tilting said roll to enable it subsequently to

co-operate with the yielding feed roll to vary the transverse angle of presentation of the blank to the skiving knife to vary the angle of bevel produced by the knife.

26. In a machine for skiving box toe blanks, a skiving knife, means for feeding and guiding a blank relatively to said knife to cause the blank to be skived along the breast and toe margins thereof, and means operative after the breast margin has been skived to vary the transverse angle of presentation of the margin to the knife to cause a narrower scarf to be produced around the toe than along the breast edge of the blank.
27. In a machine for skiving box toe blanks, in combination, a rotary cylindrical skiving knife, means including a presser roll for feeding and guiding a blank relatively to said knife to cause the blank to be skived along the breast and toe margins thereof, and means operative after one of said margins has been skived to vary the axial angle of said presser roll relatively to the skiving knife to cause the other margin of the blank to be skived at a different angle from the first margin, and means operative after the skiving of one blank has been completed to restore the initial axial relation of the presser roll relatively to the skiving knife preparatory to the skiving of another blank.
28. A machine for skiving box toe blanks having, in combination, a rotary cylindrical skiving knife, a feed roll within the knife, a presser roll without the knife co-operating with said feed roll to feed a blank past the knife, a feed table, an edge gage, a presser foot for co-operating with the feed table to cause the curved edge of the blank to be held in contact with the edge gage as the blank is fed, and means for separating said rolls and lifting said presser foot after the blank has been skived along one of its curved margins to permit the blank to be repositioned relatively to said rolls and the knife for the skiving of the other curved margin of the blank.

29. In a skiving machine of the type having a rotary cylindrical skiving knife, a feed roll within the knife, and a presser roll without the knife co-operating with said feed roll to feed the work past the knife, the combination therewith of mechanism for adapting the machine to skive box toe

blanks comprising means for swinging the blank in its own plane to change its angular relation to the rolls while it is being fed to cause the blank to be skived along one of its curved margins, and means for separating said rolls after said margin has been skived to permit the blank to be repositioned relatively to said rolls and knife for the skiving of the other curved margin of the blank.

30. In a machine for skiving box toe blanks or the like, in combination, a skiving knife, a feed table, an edge gage, continuously operative mechanism for feeding a blank across the feed table and past the knife, a presser foot adapted to bear upon the face of the blank while the blank is being fed across the table to hold the curved margin of the blank against the edge gage, means controlled by a normally inoperative clutch for rendering the feeding mechanism ineffective and for raising the presser foot to release the blank, mechanism for throwing in the clutch after the breast margin of the blank has been skived, means operative while the clutch members are engaged for repositioning the blank relatively to the knife for the skiving of the margin around the toe, and means for throwing out the clutch after the blank has been repositioned.

31. A machine for operating upon opposite marginal portions of a blank having, in combination, operating mechanism, means for feeding one marginal portion of the blank along and past the operating mechanism, and means automatically to swing the blank in its own plane to reposition the blank for operation by the same mechanism upon the opposite marginal portion thereof.

32. In a machine for operating upon a blank having a plurality of non-similar sides, the combination with operating mechanism and means for positioning the blank to present one side thereof to the operating mechanism, of means for repositioning the blank after said side has been operated upon to present another side thereof to said operating mechanism, and means for feeding the blank to advance said sides in turn past the operating mechanism.

In testimony whereof I have signed my name to this specification.

JOHN M. BENJAMIN.
